[57] ABSTRACT

Heat resistant explosives of the formula

wherein R₁ and R₂ are selected from the group consisting of H and NO₂. Compounds wherein R₁ and R₂ are prepared by contacting a picryl halide with a thiophene of the formula

wherein X is a halogen. When either or both of R₁ and R₂ are NO₂, nitration of 2,5-dipicryl thiophene can be used to prepare the desired compounds.

4 Claims, No Drawings

2,5-DIPICRYL THIOPHENES

BACKGROUND OF THE INVENTION

This invention generally relates to explosives and more particularly to explosives with excellent heat stability. 5

Use of explosives in many different types of devices is widely known in the prior art. However, despite the huge number of explosives that are known there are relatively few that can withstand high temperatures in the range of 230°-260°C or above without substantial deterioration. Since explosives in many specialized uses are subjected to temperatures of about 230°C or higher there has been a constant search for explosive materials which will not deteriorate substantially due to high 15 temperatures.

SUMMARY OF THE INVENTION

Accordingly, one object of this invention is to provide new chemical compounds. 20

Another object of this invention is to provide chemical compounds that can be used as explosives.

A further object of this invention is to provide explosive compounds which are capable of withstanding temperatures in the range of 230°-260°C and above without substantial deterioration. 25

A still further object of this invention is to provide explosive compounds which can be used in environments wherein high temperatures are a problem (i.e., where aerodynamic heating is a problem). 30

Yet another object of this invention is to provide explosive compounds which can be used in mild detonating cord and flexible linear shaped charges.

These and other objects of this invention are accomplished by providing chemical compounds of the formula 35

wherein R₁ and R₂ are selected from the group consisting of H and NO₂, which are prepared by reacting picryl bromide or any picryl halide, with a thiophene of the formula 40

wherein X is halogen or by first reacting picryl bromide with 2,5-dihalothiophene to form the 2,5-dipicrylthiophene and then nitrating using standard nitrating conditions. 45

DESCRIPTION OF THE PREFERRED EMBODIMENT

Compounds of the formula

wherein R₁ and R₂ are H or NO₂ are prepared in one 10 of two ways. One may prepare them by contacting the appropriate thiophene of the formula

wherein X is halogen with picryl bromide under the typical Ullman biaryl synthesis. Compounds wherein one or both of R₁ and R₂ are NO₂ can also be prepared by nitration of 2,5-dipicrylthiophene which is formed using the Ullman biaryl synthesis. 20

With the Ullman synthesis the thiophene is dissolved in a solvent such as nitrobenzene and copper bronze is added. The picryl bromide is then added dropwise to the above solution over a period of about one-half hour and the temperature is maintained at about 150°C. Following this the solution are purified using typical purification techniques. 25

The thiophenes wherein one or both of R₁ and R₂ are NO₂ can also be prepared by direct nitration of 2,5-dipicrylthiophene. When one of R₁ and R₂ is NO₂ 90% nitric acid at 45°C for about 10 minutes gives almost quantitative yields. When both R₁ and R₂ are NO₂ nitration by using 90% nitric acid and 30% oleum at 60°C for about 2 hours is preferred. 30

The general nature of the invention having been set forth, the following examples are presented as specific illustrations thereof. It will be understood that the invention is not limited to these specific examples but is susceptible to various modifications that will be recognized by one of ordinary skill in the art. 40

EXAMPLE 1

PICRYL BROMIDE

An amount of 355 g (3.5 moles) of reagent grade potassium nitrate was dissolved in 800 ml of 30% oleum in a 2,000 ml 3-neck round bottom flask fitted with a mechanical stirrer and a thermometer. During the addition of the potassium nitrate, the mixture was cooled and stirred on an ice bath, the temperature being kept below 60°C. When the addition was complete, the mixture was cooled to 30°C and 79 g (0.5 moles) of bromobenzene was added at such a rate as to keep the temperature below 50°C. The ice bath was then replaced by an oil bath and the reaction mixture was heated to approximately 125°C for four hours. After cooling, the mixture was drowned in crushed ice, the product was 50 collected by filtration using a sintered glass funnel and thoroughly washed with water. After drying in a warm oven, it was dissolved in 100 ml of acetone, 300 ml of methanol was added and the solution was cooled in the freeze compartment of the refrigerator. On filtration, 83.7 g of pale yellow crystalline picryl bromide, mp 120°-122°C (lit. 122°-3°C) was recovered. The filtrate was concentrated to about 150 ml by boiling on the steam bath and again cooled in the freeze compartment. 55

ment. The second crop weighed 28.0 g and melted over the range 111°-118°C. On recrystallization from acetone-ethanol, an additional 21.0 g of crystalline product, mp 120°-122°C was obtained to give a total yield melting at this temperature of 104.7 g, 71.6%. Samples melting at 122°-123°C were obtained by one additional recrystallization from acetone-methanol.

EXAMPLE 2

2,5-DIPICRYLTHIOPHENE

A stirred mixture of 19.4 g (0.08 moles) of 2,5-dibromothiophene and 45.7 g (0.72 moles) of copper bronze in 80 ml of dry nitrobenzene was rapidly heated to 145°C in a 500 ml 3-neck round bottom flask equipped with a mechanical stirrer, a thermometer and an addition funnel. Approximately one-half of a solution containing 58.4 g (0.20 moles) of picryl bromide in 150 ml of dry nitrobenzene was added over a period of 10 minutes with the temperature at 145°-150°C. The remaining half of the solution was added over a period of 25 minutes. The dark reaction mixture was then allowed to cool to 100°C and was poured into 300 ml of toluene. The mixture was cooled to 10°C in an ice bath and filtered. The insoluble residue was washed with methanol then stirred in 800 ml of 20 percent hydrochloric acid at 60°-70°C for 15 minutes. The acid-insoluble residue was removed by filtration and was washed on the funnel with dilute hydrochloric acid, water and finally methanol. The product (37.6 g), which contained unreacted copper, was stirred with 300 ml of dimethylsulfoxide at 100°C and filtered. The residue on the funnel was washed with an additional 50 ml of hot dimethylsulfoxide and the dark filtrate was treated with 20 g of activated charcoal at 100°C. The charcoal was removed by filtration and the filtrate was added slowly with stirring to 700 ml of methanol causing the product to precipitate. The suspension was cooled to 5°C on an ice bath and filtered. The bright yellow product was washed with methanol and dried at 120°C under vacuum for one hour to give 31.3 g (76.8%) of 2,5-dipicrylthiophene, m.p. 359°-360°C (d) (darkens above 300°C). This product was dissolved in 500 ml of nitrobenzene at 165°C and recrystallized by slowly cooling to room temperature. On filtering, washing with 150 ml of methanol and drying under vacuum at 130°C for 2 hours, the product was 29.1 g of golden yellow crystals, m.p. 359°-360°C (d). On adding an additional 250 ml of methanol to the filtrate and cooling in an ice bath, an additional 1.3 g of product having the same melting point was recovered. The total yield was 30.4 g (75.1%). Both crops were chromatographically pure and darkened slowly on heating above 300°C.

EXAMPLE 3

2,5-DIPICRYL-3-NITROTHIOPHENE

To a stirred volume of 250 ml of 90 percent nitric acid was added 25.3 g (0.05 moles) of 2,5-dipicrylthiophene. The temperature was then raised to 45°C to effect complete solution of the solid. The solution was stirred approximately two minutes and poured into one liter of ice water with vigorous stirring. The product was removed by filtration, thoroughly washed with water and, since the water-wet material was very difficult to handle, it was thoroughly washed with methanol on the funnel. After drying under vacuum at 120°C for 2 hours, the yield of crude 2,5-dipicryl-3-

nitrothiophene was 27.1 g (98.4%), m.p. 285°-286°C (d). Thin-layer chromatography indicated that the product was free of both the starting material and the dinitro derivative. The product was dissolved in 350 ml of hot acetone, the solution was treated with a small amount of activated charcoal and filtered. The bright yellow filtrate was concentrated by distillation until precipitation occurred (volume was about 100 ml). Methanol was slowly added with continued distillation until the temperature of the distillate reached 63°C and the volume was about 200 ml. The mixture was cooled in an ice bath, filtered and washed with methanol to give 26.3 g (95.5%) of bright yellow crystals, m.p. 287°-288°C (d).

EXAMPLE 4

2,5-DIPICRYL-3,4-DINITROTHIOPHENE BY ULLMANN BIARYL SYNTHESIS

To a slurry of 6.4 g (0.1 moles) of copper bronze and 40 ml of nitrobenzene stirred at 185°-190°C was added a solution containing 3.32 g (0.01 moles) of 2,5-dibromo-3,4-dinitrothiophene, prepared according to Monzingo, et al. and 9.9 g (0.04 moles) of picryl chloride in 40 ml of nitrobenzene dropwise over a period of five minutes. Heating at 185°-190°C was continued for ten minutes after the addition was complete. The dark mixture was cooled to 120°C, filtered and the filtrate was added to 150 ml of benzene. After cooling on an ice bath and filtering, a precipitate weighing 5.6 g was recovered. Thin-layer chromatography using benzene-acetone 85:15 as the developer showed this product to be a mixture, one component of which was 2,2',4,4',6,6'-hexanitrobiphenyl. The solid was dissolved in a minimal amount of acetone; the solution was treated with activated charcoal and filtered. Acetone was removed by distillation while benzene was slowly added causing the precipitation of a solid product. This was continued until the temperature of the distillate was 70°C. After removal from the hot solution by filtration, the product weighed 2.75 g and melted at 295°-298°C with decomposition. Recrystallization by dissolving in a minimal amount of hot acetonitrile, adding benzene to effect precipitation and cooling in ice gave a yield of 2.1 g (35%) of bright yellow crystals, m.p. 305°-306°C (d). After drying under vacuum at 130°C for 1 hour, the n.m.r. spectrum showed singlets at 7.34 and 9.31 ppm. The latter was reasonable for the four equivalent protons of 2,5-dipicryl-3,4-dinitrothiophene, but the singlet at 7.34 ppm was thought to be due to the presence of benzene in the sample, probably as benzene of solvation. Vapor phase chromatographic analysis showed this to be the case. An analytical sample was prepared by drying this material an additional 6 hours under vacuum at 130°C.

EXAMPLE 5

2,5-DIPICRYL-3,4-DINITROTHIOPHENE BY NITRATION

Two grams of 2,5-dipicrylthiophene were stirred into 30 ml of 90 percent nitric acid at 60°C. Thin-layer chromatography indicated that a small sample removed 3 minutes after solution was complete contained only 2,5-dipicryl-3-nitrothiophene. The nitric acid solution was cooled to 15°C and 10 ml 30 percent oleum was slowly added causing a rise in temperature to 50°C. The reaction mixture was then heated to 60°C for one hour

and forty-five minutes and poured onto an excess of crushed ice. The aqueous mixture was filtered to give 2.2 g of a bright yellow solid, m.p. 298°-300°C (d). Crystallization from acetonitrile-benzene yielded 2.15 g of bright yellow crystals which lost benzene of solvation after drying two hours at 140°C (see preparation of this product by the Ullmann biaryl synthesis). The dried product weighed 1.90 g (79.1%) and melted at 303°-304°C with decomposition. An additional recrystallization from acetonitrile-benzene gave 1.8g of pure 2,5-dipicryl-3,4-dinitrothiophene, m.p. 304°-305°C after drying under vacuum at 140°C. This product was identical (TLC) to that prepared by the Ullmann biaryl synthesis.

Obviously, numerous modifications and variations of the present invention are possible in light of the above teachings. It is therefore to be understood that within the scope of the appended claims the invention may be practiced otherwise than as specifically described herein.

What is claimed as new and desired to be secured by

10

Letters Patent of the United States is:

1. Compounds of the formula

15

wherein R₁ and R₂ are selected from the group consisting of H and NO₂.

16

2. The compound of claim 1 wherein both R₁ and R₂ are H.

17

3. The compound of claim 1 wherein both R₁ and R₂ are NO₂.

18

4. The compound of claim 1 wherein R₁ is H and R₂ is NO₂.
